CLAIM

(21) Appl. No.: **29/095,461**

The ornamental design for a duck massager with removable attachment, as shown and described.

(22) Filed: **Oct. 23, 1998**

DESCRIPTION

(51) LOC (7) Cl. **24-04**

FIG. 1 is a top and front perspective view of a duck massager with removable attachment, showing our new design with a massage tool attachment;

(52) U.S. Cl. **D24/214**

FIG. 2 is a side elevational view thereof, the opposite side elevational view being identical;

(58) Field of Search D24/211, 214, D24/200; 601/134, 135, 136, 137, 138

FIG. 3 is a top plan view thereof;

(56) **References Cited**

FIG. 4 is a bottom plan view thereof;

U.S. PATENT DOCUMENTS

FIG. 5 is an end elevational view thereof; and,

D. 264,754 * 6/1982 Vitrac D24/211
D. 267,042 * 11/1982 Weinberger D24/211
D. 288,847 * 3/1987 Kaeser D24/211
D. 369,219 * 4/1996 Huang D24/211

FIG. 6 is end elevational view thereof, opposite that shown in FIG. 5.
